CLAIM

The ornamental design for a drinking straw, as shown and described.

DESCRIPTION

FIG. 1 is a top, front, right side perspective view of a drinking straw of a first embodiment rotating in a clockwise rotation showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged cross-sectional view taken along line 8-8 of FIG. 4;

FIG. 9 is a top, front, right side perspective view of a drinking straw of a second embodiment rotating in an anti-clockwise rotation showing the claimed design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is an enlarged cross-sectional view taken along line 16-16 of FIG. 12;

FIG. 17 is a front, right side, top perspective view of a drinking straw of a third embodiment rotating in a clockwise rotation with a foldable section showing the claimed design;

FIG. 18 is an enlarged view of FIG. 2;

FIG. 19 is an enlarged view of FIG. 3;

FIG. 20 is an enlarged view of FIG. 10; and,

FIG. 21 is an enlarged view of FIG. 11.

The dashed broken lines in the drawing depict portions of the drinking straw that form no part of the claimed design.
